(57) **CLAIM**

The ornamental design for a lens for a light emitting diode (LED) luminaire assembly, as shown and described.

DESCRIPTION

FIG. 1 is a perspective view of a first embodiment of a lens for a light emitting diode (LED) luminaire assembly according to our new design;

FIG. 2 is a top view of the lens for a light emitting diode (LED) luminaire assembly shown in FIG. 1;

FIG. 3 is a bottom view of the lens for a light emitting diode (LED) luminaire assembly shown in FIG. 1;

FIG. 4 is a left view of the lens for a light emitting diode (LED) luminaire assembly shown in FIG. 1;

FIG. 5 is a right view of the lens for a light emitting diode (LED) luminaire assembly shown in FIG. 1;

FIG. 6 is a front view of the lens for a light emitting diode (LED) luminaire assembly shown in FIG. 1;

FIG. 7 is a rear view of the lens for a light emitting diode (LED) luminaire assembly shown in FIG. 1;

FIG. 8 is a cross-sectional view of the lens for a light emitting diode (LED) luminaire assembly shown in FIG. 1 along line 8-8 in FIG. 4;

FIG. 9 is a perspective view of a second embodiment of a lens for a light emitting diode (LED) luminaire assembly;

FIG. 10 is a top view of the lens for a light emitting diode (LED) luminaire assembly shown in FIG. 9;

FIG. 11 is a bottom view of the lens for a light emitting diode (LED) luminaire assembly shown in FIG. 9;

FIG. 12 is a left view of the lens for a light emitting diode (LED) luminaire assembly shown in FIG. 9;

FIG. 13 is a right view of the lens for a light emitting diode (LED) luminaire assembly shown in FIG. 9;

FIG. 14 is a front view of the lens for a light emitting diode (LED) luminaire assembly shown in FIG. 9;

FIG. 15 is a rear view of the lens for a light emitting diode (LED) luminaire assembly shown in FIG. 9;

FIG. 16 is a cross-sectional view of the lens for a light emitting diode (LED) luminaire assembly shown in FIG. 9 along line 16-16 in FIG. 12;

(Continued)

FIG. 17 is a perspective view of a third embodiment of a Lens for a light emitting diode (LED) luminaire assembly; FIG. 18 is a top view of the lens for a light emitting diode (LED) luminaire assembly shown in FIG. 17; FIG. 19 is a bottom view of the lens for a light emitting diode (LED) luminaire assembly shown in FIG. 17; FIG. 20 is a left view of the lens for a light emitting diode (LED) luminaire assembly shown in FIG. 17; FIG. 21 is a right view of the lens for a light emitting diode (LED) luminaire assembly shown in FIG. 17; FIG. 22 is a front view of the lens for a light emitting diode (LED) luminaire assembly shown in FIG. 17; FIG. 23 is a rear view of the lens for a light emitting diode (LED) luminaire assembly shown in FIG. 17; and, FIG. 24 is a cross-sectional view of the lens for a light emitting diode (LED) luminaire assembly shown in FIG. 17 along line 24-24 in FIG. 20.

Features disclaimed with broken lines in the figures indicate structure which forms no part of the claimed design.
